WATER COOLER FOR REFRIGERATORS

William H. Hinze, Oak Park, Ill.

Application June 23, 1932. Serial No. 618,833

7 Claims. (Cl. 62—44)

It is at present common practice, in order to provide cold drinking water, to place water containers in the food compartments of refrigerators. Usually all of the space in a refrigerator that is adapted for the storage of food is needed for that purpose. Therefore, when water containers of a size to be worth while for the purpose of providing a useful supply of drinking water are placed in the food compartments, there may not be enough room left to take care of the food. Furthermore, whenever a drink of water is desired, it is necessary to open the refrigerator and permit the cold air to flow out, thus reducing the efficiency of the refrigerator to that extent.

The object of the present invention is to make it possible to maintain a supply of cold drinking water in a refrigerator without cutting down the storage space for food and without making it necessary to open the refrigerator whenever a drink is desired.

In carrying out my invention I form in a wall of the refrigerator a large recess communicating with the cooling chamber and place in this recess a container for water that may be placed in position or removed at will; a suitable dispensing device leading to the exterior of the refrigerator being arranged for automatic connection with the container when the container is placed in the recess. After a container full of water has been placed in the refrigerator, the refrigerator need not again be opened until the container is empty and needs refilling or until it is desired to take out the container filled, or partially filled, with cold water. When it is simply desired to draw a drink of water, this is done by means of the dispensing device, without opening the refrigerator. The recess to provide storage space for the water container may be placed in any wall of the refrigerator, although in the ordinary comparatively small household unit it can probably best be placed in the door so as to permit ready access to the container and permit its easy installation and removal.

The various features of novelty whereby my invention is characterized will hereinafter be pointed out with particularity in the claims; but, for a full understanding of my invention and of its objects and advantages, reference may be had to the following detailed description taken in connection with the accompanying drawing, wherein:

Figure 1 is a front elevation of a refrigerator having my improvement applied to the door thereof; Fig. 2 is an elevation of the inner side

of the door, on a larger scale than Fig. 1; Fig. 3 is a section on line 3—3 of Fig. 2; and Fig. 4 is a section, on a greatly enlarged scale, on line 4—4 of Fig. 2.

In the drawing I have illustrated my invention as applied to the door of a refrigerator and, for the sake of brevity, shall confine the detailed description to this particular embodiment, as the door may be regarded as representative of all of the walls of the refrigerator.

Referring to the drawing, 1 represents a refrigerator of any usual or suitable construction, having a door 2. The door 2 is shown as having on the inner side a long, wide depression 3 of considerable depth. In the lower end of the depression is arranged a vertical frusto-conical cup 4 fixed to the inner end of a short horizontal pipe 5 extending from the chamber through the material of the door lying outwardly therefrom, to the exterior of the door. On the outer end of the pipe 5 is a suitable faucet or nozzle which, in the arrangement shown, is a device 6 having a swinging spout 7 that shuts off the pipe 5 when swung parallel to the face of the door, while permitting liquid to flow from the pipe through the spout of the dispensing device when the spout stands at right angles to the plane of the door. Dispensing devices of the kind illustrated are old and well known and therefore require no detailed description. Of course, instead of the particular dispensing device illustrated, a suitable faucet may be employed.

Adapted to be set into the depression or recess 3 is a large, flat container 8 that may be a bottle or any other suitable device. The container is detachably held in the recess or depression in any suitable way. In the arrangement shown, the door carries a pair of spring clips 9, 9 between which the container is pressed when set into the recess or depression, and which grip the container and hold it in place. The container is provided at that end, which is the lower end when in position on the door, with a discharge or outlet fitting 10 which may conveniently be fixed to a suitable screw cap 11 adapted to be screwed on the neck of the bottle or other container. At the free end of the element 10 is a plug or head 12, preferably composed of rubber, that may be set down into the cup-shaped part 4 associated with the dispensing device, in the manner of a stopper, and make a tight joint between the part 4 and the part 10. The outlet or discharge connection 10 may be, and preferably is, provided with a suitable shut-off valve having a handle or finger piece 13 by means of

which it may be turned. By closing the valve the container may be up-ended without allowing any of its contents to escape, so that no water will be spilled when the container is placed in the door or removed therefrom, as long as the valve is closed.

While I have illustrated and described with particularity only a single preferred form of my invention, I do not desire to be limited to the exact structural details thus illustrated and described; but intend to cover all forms and arrangements which come within the definitions of my invention constituting the appended claims.

I claim:

1. A refrigerator having a cooling chamber and a large recess in a wall of the refrigerator and opening into said chamber, a liquid dispensing device extending through said wall and having at its inner end an inlet, and a container for a liquid detachably secured in said recess and having an outlet element seated in the said inlet.

2. A refrigerator having a cooling chamber and a large recess in a wall of the refrigerator and opening into said chamber, a liquid dispensing device extending through said wall, and a container for a liquid detachably secured in said recess and having a valved outlet element coupled to the inner end of said dispensing device.

3. In combination, a refrigerator having a door, said door having a long, wide recess in the inner side communicating with the cooling chamber in the refrigerator, a liquid dispensing device extending from said recess through and fixed in the door to the exterior of the refrigerator, a container for a liquid detachably secured in said recess, a discharge nozzle or spout on said container, a manually-operated valve in said nozzle or spout, and a part on the inner end of the dispensing device to receive the nozzle or spout and cause the dispensing device to form a continuation of the nozzle or spout when the container is placed in said recess.

4. A refrigerator having a cooling chamber and a large recess in a wall thereof opening into said chamber, a liquid-dispensing device extend-

ing through said wall and having at its inner end an inlet provided with an annular seat surrounding the same, and a container for a liquid detachably secured in said recess and having an outlet element fitting against said seat.

80

5. A refrigerator having a cooling chamber and a large recess in a wall thereof opening into said chamber, a liquid-dispensing device extending through said wall and having at its inner end an inlet provided with an annular seat surrounding the same, a container for a liquid detachably secured in said recess and having an outlet element fitting against said seat, and a manual valve in said outlet element to permit the container to be placed in position or to be removed without spilling its contents.

85

6. A refrigerator having a cooling chamber and a large recess in a wall thereof opening into said chamber, a liquid-dispensing device extending through and fixed in said wall and having at its inner end an inlet, a container for a liquid detachably secured in said recess and having an outlet, and cooperating elements at the inlet end of said dispensing device and at the outlet from said container to form a liquid-tight joint between the dispensing device and the container upon the insertion of the container in said recess.

90

7. The combination with an outer wall of a refrigerator, of a liquid-dispensing device extending through and fixed in said wall and having at a point within the refrigerator an inlet, a detachable container for a liquid having an outlet, cooperating elements at the inlet of said dispensing device and at the outlet from said container to form a liquid-tight joint between the dispensing device and the container when that one of the aforesaid elements that is on the container is placed against the other of said elements, and means within the refrigerator to support said container within the refrigerator in such a position that said elements are held in engagement with each other.
